UNITED STATES PATENT OFFICE.

GEORGE B. BARTHOLOMEW, OF ASHLAND, KENTUCKY.

CUTTER-GUARD FOR WOODWORKING MACHINERY.

No. 826,465.

Specification of Letters Patent.

Patented July 17, 1906.

Application filed September 26, 1905. Serial No. 280,151.

To all whom it may concern:

Be it known that I, GEORGE B. BARTHOLOMEW, a citizen of the United States, residing at Ashland, in the county of Boyd and State of Kentucky, have invented certain new and useful Improvements in Cutter-Guards for Woodworking Machinery, of which the following is a specification.

The invention to be hereinafter described relates to cutter-guards for woodworking machines, and more particularly to such type of devices known as "surfacing" and "jointing" machines. In the practical operation of such machines it frequently happens that material is treated the width of which is not sufficient to cover the entire operating area of the cutters, so that in feeding material by hand the machine attendant is subjected to the danger of having his hands or person injured by contact with the cutters.

The general object, therefore, of the present invention is to provide a cutter-guard of simple construction which will efficiently cover the otherwise-exposed operating area of the cutters, in which also the cutter-guard shall automatically adjust itself to the different widths of material treated and be readily locked in position over the cutters or placed in convenient position out of the way when not required for service.

With these generally-stated objects in view the invention consists of the parts and combinations to be hereinafter described and then definitely pointed out in the claims.

In the drawings, Figure 1 is a plan view of an embodiment of the invention, showing the same in position over the cutters of an ordinary type of surfacing or jointing machine, parts being broken away. Fig. 2 is a similar plan view showing the cutter-guard swung from its operative position over the cutters to one side out of the way when not required for service. Fig. 3 is a side elevation of so much of a surfacing or jointing machine as necessary to show the cutter-guard applied thereto. Fig. 4 is a detail showing the lock for holding the cutter-guard in position over the cutters.

Referring to the accompanying drawings, A designates a suitable work-supporting table of any ordinary or desired form of surfacing or jointing machine, B the cutters of such machine mounted on the operating-shaft B', and C the work-guide. These parts may be of the usual or any general type, construction, or arrangement and in specific de-

tails form no part of the present invention, they being illustrated to show one application of the present invention without restriction of the invention thereto.

Rising from the work-supporting table A in proximity to the cutters B is a supporting-arm a, Fig. 3, preferably held in place by a set-screw a' beneath the table and having at its upper end the sleeve-bearing a², Figs. 1 and 2, through which passes the horizontal carrying-arm b, said arm b being adjustable in the sleeve-bearing a² and held in position by means of a set-screw a³. The carrying-arm b is preferably enlarged somewhat at its outer end b', Fig. 3, and provided with a perforation through which passes the pin d' of the turning arm d. Said pin d' extends somewhat below the end of the carrying-arm b and is surrounded by a spring d², one end 75 of which contacts with the under side of the end b' and the other end against a pin d³. (See Fig. 3.) The upper portion of end b' of the carrying-arm b is cut away or provided with a locking-shoulder b³, and the under portion of the end d⁴ of the turning arm d is likewise cut away or provided with a shoulder d⁵, such shoulders being so disposed that the spring d² will normally hold them in locking engagement to prevent rotative movement of the turning arm d, and yet by an upward, pull or lift of the arm d will enable the shoulders b³ and d⁵ to be disengaged and the arm d to be swung about its connection with arm b for a purpose that will presently appear.

To the turning-arm d are secured the guard-supports e², Figs. 1 and 2, such guard-supports being passed through the perforated lugs e' on the guard-plate E and a spring 95 being mounted upon each of said guard-supports between such lug and the connection of the supports to the turning arm d, whereby the normal tendency of the springs e² is to force the guard-plate E from the arm d. The outer ends of the guard-supports e are provided with suitable stops—as, for instance, the nuts e³.

The guard-plate E, Fig. 3, is formed with an upward bend or curve substantially 105 through its width, so that it effectually clears the cutters B, while at the same time its end portions e⁴ may rest upon and find stable support upon the work-table A. (See Fig. 3.)

That end of the guard-plate E next to the work-guide C is provided with an up-

wardly-turned flange E' , and both it and the plate E have an outwardly-turned portion, as at E^2 , on that side of the guard-plate to which the work or board, as indicated in dotted lines at D , Fig. 1, is introduced. The effect of this is that the operative is not called upon to handle the cutter-guard when it is in operative position, as shown in Fig. 1, because the piece to be cut, D , is merely fed endwise along the work-guide C , and as it comes in contact with the curved portion E^2 of the guard-plate such guard-plate is forced outwardly against the tension of the springs e^2 .

From the construction described it will be noted that when the guard-plate E is in its operative position covering the cutters the turning arm d is substantially parallel with the edge of the work-table, and the supports e hold the guard-plate in position, so that any outward or inward movement thereof is in substantial parallelism with the axis of the operating-shaft B' of the cutters, so that at all times the guard-plate effectually covers all portions of the cutters not protected by the work itself. It will be further noted that when the guard-plate is in its operative position, Fig. 1, the locking device comprising the shoulders b^3 and d^5 and their coacting parts effectually hold the guard-plate in the position just described, so that any force tending to move the plate away from the work-guide C simply effects a bodily outward movement of the guard-plate E parallel to the operating-shaft of the cutters, so that there is at no time during the operation of the cutters any exposed portion thereof which might be liable to cause injury to the workmen. When it is desired to dispense with the service of the guard-plate, the turning arm d is lifted sufficiently to permit disengagement of the shoulders b^3 and d^5 , whereupon the guard-plate E may be swung with its connected parts away from the cutters into the position indicated in Fig. 2.

In devices of this character the workmen are very liable to place their hands upon the guard-plate E while manipulating the work to be cut, and the present device, comprising the curved guard-plate, enables such guard-plate to find stable bearings at the points e^4 , hereinbefore described, thereby preventing any downward deflection of the guard-plate when thus handled. The present device also is well adapted for application to any surface-joining or jointing machine by merely providing a support for the upright a on the table of the machine, the remaining portion of the cutter-guard being self-contained and applicable to or detachable from such machine without special appliances or changes in the machine.

Having thus described my invention, what I claim, and desire to secure by Letters Patent of the United States, is—

1. In a cutter-guard for woodworking-

machines, the combination of an integrally-formed guard-plate having an upwardly-curved central portion and horizontally-extending side portions to normally rest upon the machine-frame when the guard is in operative position protecting the cutter, a supporting-arm adjustably secured to the machine-frame and extending outwardly therefrom, a horizontally-turning arm having a vertical pivotal connection with the projecting end of the supporting-arm, connections between the horizontally-turning arm and the guard-plate, and a lock disposed between the end of the supporting-arm and turning arm.

2. In a cutter-guard for woodworking machines, the combination of a supporting-arm, a horizontally - swinging turning arm having a vertical pivotal connection with said supporting-arm, a lock for holding said turning arm in its operative position, said lock comprising a pin on said turning arm and co-operating shoulders on said supporting-arm, operating-arms mounted horizontally on said turning-arm, said operating-arms having slidably mounted thereon a cutter-guard, said cutter-guard comprising a plate having an upwardly-curved central portion, an integrally-formed curved guide-flange, an integrally-formed flat horizontal supporting-flange on either side of the curved portion, and springs interposed between the cutter-guard and the turning arm and surrounding the operating-arms, said springs acting to hold the guard yieldingly in its extended position.

3. In a cutter-guard for woodworking machines, the combination of a supporting-arm, a horizontally-swinging turning arm having a vertical pivotal connection with said supporting-arm, a lock for holding said turning arm in its operative position, said lock comprising a pin on said turning arm and co-operating shoulders on said supporting-arm, operating-arms mounted horizontally on said turning arm, said operating-arms having slidably mounted thereon a cutter-guard, said cutter-guard comprising a plate having an upwardly-curved central portion, an integrally-formed curved guide - flange, an integrally - formed horizontal supporting-flange on either side of the curved portion, a perforated ear mounted on each of said supporting-flanges and adapted to slidably receive through such perforation one of the operating-arms and a spring mounted upon such supporting-arm and interposed between the lug and the turning arm whereby the cutter-guard is yieldingly held in its operative position.

In testimony whereof I affix my signature in presence of two witnesses.

GEORGE B. BARTHOLOMEW.
